UNITED STATES PATENT OFFICE.

LOUIS JEAN FRANÇOIS FILLOUX, OF LE HAVRE, FRANCE.

GUN CARRIAGE.

Application filed January 12, 1922. Serial No. 528,815.

To all whom it may concern:

Be it known that I, LOUIS JEAN FRANÇOIS FILLOUX, a citizen of the Republic of France, residing at Le Havre, Seine-Inférieure, France, 2 Rue Dubocage de Bleuville, have invented a new and useful Improvement in Gun Carriages; and I do hereby declare the following to be a full, clear, and exact description of the same.

10 This invention relates to artillery with gun-carriages of the split trail type and has for its object to permit the easy travel of the gun even over bad terrain; this improvement is characterized essentially by the

15 direct mounting on each of the trail members of a chain-track, which serve for the travel of the carriage over bad surfaces. These chain-tracks, following spreading and swinging movements of the trails, can

20 not, in spite of their length which is much greater than that of the usual wheels, obstruct the spreading of the trails as would be the case if they were part of the axle or of the bottom carriage. The invention

25 consists, further, in the arrangement at the front of the bottom carriage, of a front axle and wheels of normal track mounted in a detachable manner, which wheels serve for the travel of the gun-carriage along a

30 road, and of a screw-jack provided with a preferably knee jointed shoe or plate of suitable dimensions and which forms, during firing, a point of forward support and enables at the same time contact between

35 the chain tracks and the ground to be dispensed with.

By reason of these arrangements, there is obtained a piece of artillery easily transportable by road and over all kinds of terrain and affording all the advantages of split trail carriages in manoeuvring and firing.

The annexed drawing represents by way of example, a piece of artillery with split trail, the members of which are jointed to the bottom-carriage by axes, and provided with the improvement forming the subject of the present invention.

Figure 1 is a view in elevation of the piece of artillery in the position for travelling by road.

Figure 2 is the corresponding plan view.

Figure 3 is a side elevation of the gun in position for travel over bad terrains.

Figure 4 is the corresponding plan view.

Figure 5 is a view in elevation of the gun set up for firing.

Figure 6 is the corresponding plan view.

According to the present invention, the split-trail members a a^1 of the gun-carriage are provided each with an endless chain-track b b^1 , either fixed rigidly upon the corresponding member or mounted, as more particularly shown in Figure 2, by the aid of tenons c c^1 , c^2 c^3 fast to the frames of the chain-tracks b b^1 and entering mortises d d^1 , d^2 d^3 which are fast to the members a a^1 . When this last mentioned arrangement is employed, the gun-carriage can be relieved of its chain tracks during transport by road.

The chain-tracks b b^1 serve for the transport of the gun over bad surfaces (Figures 3 and 4) and follow the movements of the members a a^1 (Figures 5 and 6) during the setting up and firing operations.

The frame or bottom-carriage e upon which the trail-members a a^1 are jointed is provided with a forward prolongation e^1 at the extremity of which is mounted in a detachable manner an axle f provided with wheels f^1 ; these wheels serve for the transport of the gun along roads when its trail-members a a^1 have been swung together and rest, as customary, upon a limber or forecarriage g which may be self-propelled or hauled.

Upon the prolongation e^1 of the bottom-carriage is also mounted the screw-jack h which serves as a front support for the gun when set up for firing, the contact of the screw-jack with the ground is effected by the intermediary of a shoe or plate h^1 of suitable dimensions.

The chain-tracks b and b^1 are preferably so designed and provided that the centre of gravity of the whole mass is situated in the middle transversal plan of the chain-track devices, so that traction will be effected by directly hooking or securing the junction of the members a a^1 to the hauling vehicle g^1 without a forecarriage (Figure 3). Thus one can then easily avoid having to move back the gun upon the split-trail to bring and fix it into the position for road travel.

The setting up for firing is effected by raising the front of the gun-carriage by means of the screw-jack h (Figure 5) which continues to support the gun-carriage during firing. The gun-carriage then rests on

the ground by means of the screw-jack and the extremities of the trail-members a a^1 (Figure 5). The weight of the so lifted chain-tracks is entirely utilised for obtaining stability, and if these chain-tracks comprise springs, the latter are relieved from the effects of the firing strains.

The raising by the screw-jack of the front part of the gun-carriage enables the height 10 of the gun-trunnions to be increased during firing and consequently facilitates high-angle fire. The use of a screw-jack to raise the front of the chain-track fitted gun-carriage into the set up position affords, in the 15 case of this invention, quite special advantages. Without this screw-jack the gun-carriage would tend to rest on the ground:—
 (a) by the two ends of the members a a^1 ;
 (b) by the lower parts of the chain- 20 tracks; the latter by reason of their length do not behave as wheels do, which latter have each only one point of contact with the ground, and therefore this arrangement would be possible only on absolutely flat 25 ground or would require a levelling of the ground inconsistent with rapidity in setting up the gun.

Lastly, without departing from the spirit of the invention, the chain-tracks can be 30 mounted on a framework capable of oscillating relatively to the members a a^1 about an overhung axle rigidly mounted on each of the trail members.

What I claim is:—

35 1. A gun carriage of the split trail type comprising, in combination, a frame, two trail members pivoted thereon, and a chain track directly mounted, independently of the trail pivot, on each of said trail members, for the purpose described.

40 2. A gun carriage of the split trail type comprising, in combination, a frame, two trail members pivoted thereon, and a chain track directly and detachably mounted, independently of the trail pivot, on each of said trail members, for the purpose described.

45 3. A gun carriage of the split trail type comprising, in combination, a frame, two trail members pivoted thereon, and a chain track directly and rigidly mounted on each of said trail members, and independently of the trail pivot, for the purpose described.

50 4. A gun carriage of the split trail type comprising, in combination, a frame, two trail members pivoted thereon, and a chain track directly, detachably, and rigidly mounted on each of said trail members, and

independently of the trail pivot, for the purpose described.

5. A gun carriage of the split trail type 60 comprising, in combination, a frame, two trail members directly and pivotally connected to the frame, and a chain track directly mounted independently of the trail pivot, on each of said trail members, for 65 the purpose described.

6. A gun carriage of the split trail type comprising, two trail members, and a chain track directly mounted on each of said members, in combination with raising means arranged at the front part of the gun carriage. 70

7. A gun carriage of the split trail type comprising, two trail members, and a chain track directly mounted on each of said members, in combination with a screw jack arranged at the front part of the gun carriage. 75

8. A gun carriage of the split trail type comprising, two trail members, a chain track directly and detachably mounted on each of 80 said trail members, in combination with raising means arranged at the front part of the gun carriage.

9. A gun carriage of the split trail type, comprising, two trail members, a chain track 85 directly mounted on each of said trail members in combination with an axle positionable at the front part of the carriage, road-wheels detachably mounted on said axle, and a screw-jack arranged at the front part of 90 the gun carriage.

10. A gun carriage of the split trail type, comprising two trail members, a chain track directly mounted on each of said trail members, in combination with an axle positionable at the front part of the carriage, road-wheels, being detachably mounted on said 95 axle.

11. A gun carriage of the split trail type, comprising, two trail members, a chain track 100 directly and detachably mounted on each of said trail members, an axle positioned at the front part of the carriage, road-wheels detachably mounted on said axle, and a screw-jack arranged at the front part of the gun 105 carriage.

In testimony whereof I have signed my name to this specification in the presence of two subscribing witnesses.

LOUIS JEAN FRANÇOIS FILLOUX.
